(57) **CLAIM**

The ornamental design for a display device with graphical user interface for a recent transactions flyout, as shown and described.

DESCRIPTION

The sole FIGURE is a view of the display device with graphical user interface for a recent transactions flyout according to the invention.

The elements shown with dashed lines are for illustrative purposes only showing an example interface environment and form no part of the claimed design. The dashed line in the third icon that is referenced by the recent transactions flyout does form a part of the claimed design.

The dot dashed line represents a boundary of the recent transaction flyout shown for illustrative purposes and forms no part of the claimed design,

The broken lines along the outer perimeter represent a display device and form no part of the claimed design. All other broken line elements illustrate unclaimed elements of the graphical user interface.
